W. A. STOCKDALE,
PICTURE HANGER,
APPLICATION FILED JAN. 29, 1917.

Patented Dec. 25, 1917.

William A. Stockdale
Inventor

By *Geo. P. Kimmel.*

Attorney

UNITED STATES PATENT OFFICE.

WILLIAM A. STOCKDALE, OF CAMBRIDGE, OHIO.

PICTURE-HANGER.

1,251,130.

Specification of Letters Patent. Patented Dec. 25, 1917.

Application filed January 29, 1917. Serial No. 145,196.

To all whom it may concern:

Be it known that I, WILLIAM A. STOCKDALE, a citizen of the United States, and resident of Cambridge, in the county of 5 Guernsey and State of Ohio, have invented certain new and useful Improvements in Picture-Hangers, of which the following is a specification.

The present invention relates to the class 10 of cards, pictures, and sign exhibiting and has particular reference to new and useful improvements in picture hangers.

The primary object of my invention is to provide a hanger which will securely support a picture or a display rack, and which will always retain the picture, etc., in a level 15 position.

Another object of my invention is to provide a device of the class mentioned which 20 is adapted to be secured to the wall without injuring or materially marring the same.

A still further object of my invention is to provide a picture hanger, that is so constructed, that the picture may readily be detached therefrom.

Other improvements and novel details in the construction and arrangement of the various parts of the apparatus will be brought out more in detail in the description 30 to follow, which, for a clear understanding of the invention, should be considered in connection with the accompanying drawing, forming a part hereof, and wherein is disclosed, for the purpose of illustration, convenient and satisfactory embodiments of the 35 invention. It is to be noted, in this connection, that minor changes in the construction and arrangement of the various parts may be made without departing from the spirit 40 of the invention or the principle of operation of the various parts.

In the drawings:

Figure 1 is a perspective view of my invention, showing the same attached to a 45 wall;

Fig. 2 is a side elevation of the same, and Fig. 3 is a sectional view of Fig. 2 on the line 3—3.

Referring now more particularly to the 50 drawings, wherein like reference characters designate corresponding parts throughout the several views thereof, 1 designates a wall and 2 the body of a substantially U-shaped frame member having laterally extending 55 arms 3, the said arms having extensions 4 extending laterally of the arms provided

with projections 5 extending vertically therefrom, these projections being adapted to receive the eye screws 6 which are attached to the picture or display rack desired to be attached to the wall.

The supporting means used in connection with my invention comprises a sheet metal head-piece designated 7 provided with a slot 8 intermediate the ends and adjacent 65 the edge 9 thereof adapted to be slid over a nail 10 or other suitable securing means.

The free ends of the said head-piece are coiled as at 11 and 12 adapting the same to receive the laterally extending arms 3 to retain the same in the desired position, the 70 lateral extensions 4 limiting the downward movement of the U-shaped frame. The upper portion of the head-piece is bent laterally thereof as at 13 to provide reinforcing means for the said plate.

The base-plate of my invention comprises a sheet metal plate looped intermediate its ends as at 14 and having the free ends thereof flexed as at 15. The said end portions 80 are provided with an aperture centrally thereof to receive a nail 16 or any common form of securing means.

The mode of attaching my picture frame is as follows; first the head-piece designated 85 7 is secured to the wall over the screw or nail 10 which previously to so attaching has been securely fastened to the U-shaped supporting frame. The next step is to rigidly secure the base-plate 15 by means of the 90 screw 16. The picture hanger is now ready to receive the picture or other display rack. It is of course obvious that the extensions 5 are adapted to receive the eye hooks 6 which are attached in spaced relation to the picture 95 frame 17.

From the above description taken in connection with the accompanying drawings it will be seen that I have provided a picture hanger in which the number of parts are 100 few, the construction simple, the cost of production small, and efficiency and operation high.

Having thus fully described my invention, what I claim as new and desire to secure by Letters Patent is:—

1. The combination with a picture frame having eye screws associated therewith in spaced relation, of a substantially U-shaped frame comprising, a body portion, arms extending laterally therefrom, an extension formed on said arms adjacent the ends bent

laterally thereof, projections formed on the free ends thereof extending vertically of said extensions, a sheet metal head-piece having a slot formed therein intermediate its ends and adjacent the lower edge thereof, the ends of said head-piece being coiled to receive the said arms, and a base-plate adjacent the body of the U-shaped frame, said base-plate having an opening therein providing a means for attaching the same in a rigid position.

2. The combination with a picture frame, and a pair of eye screws secured thereto in spaced relation, of a substantially U-shaped frame, a base plate adapted to be secured to a wall, one end of the plate being coiled about the U-shaped frame to hingedly secure the same to the wall, projections formed on said frame adapted to engage said eye screws, and means associated with said U-shaped frame to detachably secure the same to a wall.

3. The combination with a picture frame,

and a pair of eye screws secured thereto in spaced relation, of a substantially U-shaped frame member, a sheet metal head-piece having a slot therein intermediate its ends and adjacent the lower edge thereof, the ends of said head-piece being coiled to receive the U-shaped frame member, and a base-plate flexed intermediate its ends and adapted to secure the said U-shaped frame in a rigid position.

4. The combination with a picture frame, and a pair of eye screws secured thereto in spaced relation, of a substantially U-shaped frame, a head-piece adapted to be rigidly secured to a wall and detachably associated therewith, the ends of the head-piece being coiled about said U-shaped frame, and a base plate flexed intermediate its ends adapted to receive said U-shaped frame and secure the same to the wall.

In testimony whereof, I affix my signature hereto.

WILLIAM A. STOCKDALE.

Copies of this patent may be obtained for five cents each, by addressing the "Commissioner of Patents, Washington, D. C."
